US00D860679S

(12) **United States Design Patent** (10) Patent No.: **US D860,679 S**
Green et al. (45) Date of Patent: ** Sep. 24, 2019

(54) **DISPLAY STRUCTURE**

(71) Applicant: **Apple Inc.**, Cupertino, CA (US)

(72) Inventors: **Christopher M. Green**, Woodside, CA (US); **Sam Brown**, Sunnyvale, CA (US); **Kully Kraig Mandon**, San Francisco, CA (US); **Casey Feeney**, Los Gatos, CA (US); **Jean-Marc Gady**, Los Altos, CA (US); **Bridget Cinquegrano**, San Francisco, CA (US); **Taylor Hoff**, San Francisco, CA (US); **Kristen Ernst**, Campbell, CA (US)

(73) Assignee: **Apple Inc.**, Cupertino, CA (US)

(**) Term: **15 Years**

(21) Appl. No.: **29/632,248**

(22) Filed: **Jan. 5, 2018**

Related U.S. Application Data

(63) Continuation of application No. 29/580,750, filed on Oct. 12, 2016, now Pat. No. Des. 809,319, which is a (Continued)

(57) **CLAIM**

The ornamental design for a display structure, as shown and described.

DESCRIPTION

FIG. 1 is a top right perspective view of a display structure showing the claimed design;

FIG. 2 is a bottom left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the display structure or environment that form no part of the claimed design.

The dot-dash broken lines in the figures show boundaries that form no part of the claimed design.

1 Claim, 6 Drawing Sheets

Related U.S. Application Data

continuation of application No. 29/526,385, filed on May 8, 2015, now Pat. No. Des. 769,021.
